UNITED STATES PATENT OFFICE.

• FRANK P. DAUGHADAY, OF CHARTLEY, MASSACHUSETTS, ASSIGNOR TO FREEMAN-DAUGHADAY COMPANY, OF CHARTLEY, MASSACHUSETTS, A CORPORATION OF MASSACHUSETTS.

BELT BUCKLE.

Application filed December 5, 1924. Serial No. 754,148.

To all whom it may concern:

Be it known that I, FRANK P. DAUGHADAY, a citizen of the United States, residing at Chartley, in the county of Bristol and State 5 of Massachusetts, have invented certain new and useful Improvements in Belt Buckles, of which the following is a specification.

This invention relates to an improvement in the construction of buckles; and has for 10 its object to provide simple and effective means for mounting a pearl or other non-metallic front plate on a metal buckle front by means of solder, in such a way that the fastening means will be entirely concealed.

15 A further object of this invention is to recess the front plate of the metal buckle in a shape to receive the outline of the pearl front plate so as to set the inner face of the pearl below the plane of the front plate of 20 the buckle to hide the joint between the two and protect the edges of the pearl when set in the buckle.

With these and other objects in view, the invention consists of certain novel features 25 of construction, as will be more fully described, and particularly pointed out in the appended claims.

In the accompanying drawings:

Figure 1 is a perspective view illustrating 30 my improved buckle with a plate of pearl set into a recess in the front plate of the buckle.

Figure 2 is a perspective view showing the back of the pearl plate as provided with 35 recesses for the reception of metal inserts by means of which the pearl may be connected by solder to the metal plate of the buckle.

Figure 3 is an enlarged view of the metal 40 member which is adapted to be swaged and so spread and fixed into the recesses in the back of the pearl without the use of cement.

Figure 4 is a disc of solder of a diameter 45 about that of one of recesses in the back of the pearl plate.

Figure 5 is a greatly enlarged view illustrating the metal member as swaged into a recess in the back of the pearl also illustrating the solder as having been fused in 50 the recess to attach the metal member in the pearl with the metal of the buckle.

Figure 6 is a sectional elevation on line 6-6 of Figure 1 illustrating the pearl plate 55 as inserted into a recess formed in the front plate of the buckle to receive it.

It is found in the practical construction of belt buckles, in some instances, desirable to insert or attach a plate of pearl or other non-metallic material to the front face of the metal buckle, by a soldering operation, and to accomplish this in a simple and effective way, I have provided one or more recesses in the rear face of the pearl plate, each of which recesses is undercut and into this recess I swage and so spread and fix a metal 60 cup-shaped member, and then connect the metal in this pearl to the metal of the buckle by solder; and the following is a detailed description of one embodiment of my present invention:—

With reference to the drawings, 10 designates the body portion of a metal buckle, which is provided with a front plate 11 preferably recessed as at 12 for the reception of a plate of pearl 13, or other similar 75 non-metallic material, the outline of the recess being preferably that of the pearl plate to form a setting for the same, whereby the inner surface of the pearl is set below the plane of the outer surface of the front plate 80 of the buckle, the edge wall of the recess then serving as a protection for the non-metallic member.

It is found in practice desirable to secure 85 this pearl plate to the metal buckle plate by solder, and in order to accomplish this in a simple and effective way, I have provided two recesses 14, the side walls of which are preferably undercut, as best illustrated in Figure 5, and I also provide a metal cup-shaped member 15, having relatively thin walls as best illustrated in Figure 3, having a beveled edge 16 and a bottom or base plate 20, whereby when forced into the undercut recess 14, the edge 16 is caused to spread and 90 the side wall 17 thereof engages the undercut walls of the recess, whereby this cup member is securely bound in the recess without the use of cement.

The side walls of the cup shaped member 15 being of less height than the side walls of the recesses 14 thereby providing a recess between the base 17 of the cup shaped member 15, when the cup shaped member is swaged into the recesses 14 of the plate 13, and the face of plate 11 for the reception therein of a thin disc of solder 19 for securing the plates together.

This cup member when swaged into this recess is of a depth less than that of the 110

recess leaving a space 18 into which the disc of solder 19 is positioned, then when the pearl is positioned in the recessed portion of the buckle a torch or other heat is applied to the back of the buckle directly beneath the solder 19 and this solder is caused to fuse and so unite the metal in the pearl with the metal of the buckle and so securely fix the pearl plate to the buckle front in such a way that the securing means is entirely invisible.

My improved means of applying a pearl plate to the front of a buckle, is very simple, practical and effective.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A belt buckle having a front plate of metal, an ornamental non-metallic plate recessed in its back, and a metal member of a depth less than that of said recess fixed therein, said recess also being of a depth to receive a portion of solder by which when fused said non-metallic plate is fixed to said front plate of the buckle.

2. A belt buckle having a front plate of metal provided with a recess, an ornamental pearl plate having an outline of said recess and set therein, a metal member fixed in a recess in the back of the pearl plate, and a portion of solder also in said recess by which when fused the metal in the pearl and that of the buckle are united to retain the pearl in its recess in the buckle.

In testimony whereof I affix my signature.

FRANK P. DAUGHADAY.
